UNITED STATES PATENT OFFICE.

FRANK E. SMITH, OF DELPHOS, OHIO.

HOLDING ATTACHMENT FOR BABY CHAIRS.

Application filed January 7, 1922. Serial No. 527,638.

To all whom it may concern:

Be it known that I, FRANK E. SMITH, a citizen of the United States, residing at Delphos, in the county of Allen and State of Ohio, have invented certain new and useful Improvements in Holding Attachments for Baby Chairs, of which the following is a specification, reference being had to the accompanying drawings.

10 This invention relates to holding attachments for baby chairs.

An important object of the invention is to provide a device of this character which may be readily attached to a chair without in 15 any manner altering the construction thereof.

A further object of the invention is to provide a device of this character which may be very cheaply and readily constructed and 20 which is readily adjustable.

Other objects and advantages of the invention will become apparent throughout the course of the following description.

In the accompanying drawings, wherein 25 for the purpose of illustration I have shown the preferred embodiment of my invention and wherein like reference characters designate like parts throughout.

Figure 1 is a plan view showing a holder 30 constructed in accordance with my invention attached to a chair;

Figure 2 is a plan view of the holder detached;

Figure 3 is a side elevation thereof;

35 Figure 4 is a section on the line 4—4 of Figure 2; and

Figure 5 is a section on the line 5—5 of Figure 3.

In the present embodiment of my invention 40 I form the holder by employing a single strand of wire which is initially bent to form a compound semi-circular loop 10. The ends of the wire at the central portion of one of the branches of the loop are twisted 45 together, as at 11, and inclined downwardly and forwardly from the loop 10. At the bottom of this twisted portion, the purpose of which will hereinafter appear, the wires are diverged, as at 12, and bent back under 50 the loop and under the portion 11 forming a slide 13.

The ends of the wire are bent back upon the slide portion 13 and inclined downwardly therefrom toward their free ends.

55 Intermediate these ends 14 a ratchet rack 15 is disposed having the shoulders of the teeth

thereof facing the forward end of the device. This rack may be secured to the wires 14 in any suitable manner, as for example, by soldering, as indicated at 16. The ends of 60 the wires 14 are provided with finger loops 14^a.

A guide 17 is provided comprising a strip of metal having the edges thereof bent to form flanges 18 overlying the strip in spaced 65 relation thereto. Adjacent the forward end of the guide 17, a cross bar 18^a is secured to the flange 18. This plate or guide 17 is adapted to be secured to the under surface 70 of the chair seat, indicated at 19, by means 75 of securing elements 20 extending through openings formed in the guide.

When the plate is secured in position, the slide 13 may engage in the grooves formed by the guide-plate flanges 18 and the device 75 forced inwardly by the hand until the holding device formed by the semi-circular loop 10 engages against the body of the child sufficiently to prevent any undue movement. Since the ends 14 of the wire have been inclined downwardly they will cause the ratchet carried thereby to engage against the cross bar 18^a and will lock the holding device in any adjusted position desired. When 80 it is desired to release the holding device 85 this may be accomplished by engaging the finger loops 14^a with the hand and slightly elevating the ends 14 sufficiently to disengage the teeth of the rack 15 from the cross bar 18^a. When the holding device is engaged 90 against the body of the child, the downwardly inclined portion 11 which forms a support for the holding device serves to prevent the child turning in the chair or sliding 95 from the chair.

From the foregoing it is believed to be obvious that I have constructed a holding attachment for chairs which is extremely easy to operate and adjust and which may be very cheaply constructed. It will likewise be obvious that many changes are possible in the shape, size and arrangement of the various parts of my device without in any manner departing from the spirit of my invention or the scope of the subjoined 100 claims.

I claim:

1. A holding attachment for baby chairs and the like comprising a guide to be attached to the under surface of a chair seat, 110 a slide engaged in the guide embodying an elastic shiftable extension provided with a

ratchet rack normally engaging a portion of said guide and preventing movement of said slide in one direction, said slide being removable from said guide by movement in 5 the opposite direction, and a holder carried by said slide and adapted to engage the body of the occupant of the chair.

2. In a holding attachment for chairs and the like, a guide secured to the under surface 10 of a chair seat, a holder comprising a single strand of wire bent centrally to form a portion for engaging the body of a per-

son seated in the chair and a portion inclining downwardly between the legs of the person, the extremities of the wire being 15 spaced and forming a slide engaging in said guide, the end portions of said extremities being bent back upon the slide forming portions and having secured thereto a ratchet rack, and a cross bar carried by the guide 20 and with which the ratchet rack coacts.

In testimony whereof I hereunto affix my signature.

FRANK E. SMITH.
